UNITED STATES PATENT OFFICE

BARNEY ETS HOKIN, OF CHICAGO, ILLINOIS

HOME GOLF GAME

Application filed September 11, 1930. Serial No. 481,290.

An object of this invention is to provide apparatus for a miniature golf game suitable for use on a floor rug, on a lawn, or other suitable nearly level surface.

Another object is to provide such apparatus with an assortment of hazards of various kinds which will test the skill of the player, and which will penalize his shots which are improperly made.

Another object is to provide a simple and convenient form of golf tee which is a part of said apparatus.

These and other objects, as will hereinafter appear, are accomplished by this invention which is fully described in the following specification and shown in the accompanying drawings, in which—

Figure 1 is a plan view of a series of devices embodying the invention arranged for play on a carpet or other level surface;

Fig. 2 is an enlarged perspective view of one of the devices;

Fig. 3 is an enlarged section on the broken line 3—3 of one of the devices shown in Fig. 1;

Fig. 4 is a partial transverse section on the broken line 4 of another of the devices of Fig. 1; and

Fig. 5 is a similar view of a section on the line 5 of Fig. 1.

In Fig. 1 is shown five embodiments of the invention disposed in such a way as to provide nine holes of a miniature golf game, the path of travel of the golf ball from the tee to the cup in each hole being indicated by dotted lines and arrows which are numbered from 1 to 9 in rotation, one for each hole. Each device is also marked by a similar numeral adjacent the hole to indicate to the player the order in which the holes are to be played.

Referring now to Fig. 1, the five devices A, B, C, D, E are preferably substantially similar in general contour but vary in details of construction, as will be pointed out. For example, E is shown in enlarged perspective in Fig. 2, and is made preferably of sheet metal with ends 13, 14 lying substantially flat so as to rest upon any flat surface, such as a rug, on which it is placed. The central portion 15 is raised with inclined portions

16, 17 at each end connecting the central portion with the flat ends 13, 14. Sides 18, which are preferably substantially vertical, depend from the central portion 15. This raised central portion is provided with two “cups” or openings 19, 20, which have curved or outwardly and downwardly inclined bottoms 21, 22 so that when the golf ball is putted into the cup it rolls down and out through openings 23, 24 in the side or end of the device onto the floor at one side of the cup so as to be in position to be played on the next hole. These inclined bottoms of the cups may be set so as to discharge balls either at the end or at the side of the device, both forms being shown in Fig. 2.

In starting play, the ball F is first teed up on the raised tee 25, preferably formed integral on the device A (Fig. 4), and is driven from this tee toward the first cup 1 in the device B. Transverse hazards 26, 27 are raised above the device B to provide a “water hole” therebetween so that a player having his ball stop between these hazards is penalized two shots, as when he drives into a water hazard in actual golf. After the ball is putted into this cup it falls to the bottom and rolls out and to the right, as indicated by the dotted line, to the point G. The player then puts the ball along the dotted line marked 2 in an endeavor to have it stop in front of the hole marked 2, so that on his next shot he can putt it straight into that cup.

The remaining holes are played in substantially the same way except for variations in the direction and distance between holes, differences in hazards, and the like. In the device D, for example, the ball must pass over the arched and corrugated bridge 28 before it reaches cup 3.

Each of the devices is provided with a series of “bunkers” 29, 30, 31, etc., which are shown on the device E of Fig. 2. These may assume various shapes and sizes, and may be arranged to serve as hazards for stopping or deflecting the golf ball if improperly driven, or they may serve to define lanes through which the golf ball may travel on its path to the cup. These bunkers or guides may be struck up from the sheet metal plate,

or they may be made as separate pieces and secured thereto as by soldering or welding.

While the embodiment of the devices illustrated is preferably made of sheet metal, it will be understood that any other suitable material may be used, such as cardboard, papier-mâché, wood, rubber, or composition, or combinations of these. Where some of these materials, such as wood, rubber, or papier-mâché, are used, the device may not be made of hollow construction as illustrated, but may be made solid or nearly so.

Additional hazards are provided in the form of wickets 32, as shown on device D (Fig. 5), which have an opening 33 through which the golf ball must be driven in play. Tunnels 34 of sheet metal may be placed between holes through which the ball must be played.

In playing this home golf game, the devices are disposed in some such form as that shown in Fig. 1 upon a rug, a lawn, a hard sand beach, or the like, which is substantially level. In actual play, these devices are separated by much larger distances than that shown in Fig. 1, wherein they are closely grouped for the sake of better illustration.

After completing each hole the score made for that hole is entered on a suitable score card for the purpose (not shown), and the player then shoots the ball from the point where it stopped after emerging from the last cup. He then proceeds to play the next several holes in this way, keeping the score of each hole as played and adding up the total score at the end so as to compare it with scores he or others have previously made, or with a predetermined "par" of the course.

The location and form of the various hazards adds very materially to the enjoyment of the game due to the greater skill required to properly play the ball to avoid these hazards. Thus it will be seen that a very simple and delightful game of home golf has been provided by this invention, and one which can be played simultaneously by several persons.

While I have shown and described but a few embodiments of my invention, it is to be understood that it is capable of many modifications. Changes, therefore, in the construction and arrangement may be made which do not depart from the spirit and scope of the invention as disclosed in the appended claims.

I claim:

1. In units for a miniature golf game, each unit adapted to lie on a relatively smooth surface and having a raised platform portion with a cup simulating opening adjacent one end thereof whereby to provide a substantial ball rolling surface as an approach to the cup simulating opening, a chute communicating with said opening to direct a ball from said unit into playing position with respect

to another unit, inclined surfaces leading up to the platform adjacent the opposite ends thereof, and a plurality of spaced and angularly positioned hazards on said ball rolling surface, some of which hazards are arranged about the opening so as to form a path for a ball when the ball is played up on the platform portion from one end to the unit and to form a guard for said opening when the ball is played up on the platform from the opposite end of the unit.

2. In units for a miniature golf game, each unit adapted to lie on a relatively smooth surface and having a raised platform portion, inclined surfaces leading up to opposite ends of said platform, said platform having two diagonally spaced cup simulating openings, one adjacent each inclined surface, chutes communicating with each of the openings and arranged to discharge balls from different sides of said device into playing position with respect to other units, path forming hazards on said platform and inclined surfaces to influence the progress of the ball toward the cup simulating openings.

3. A unit for a miniature golf game so constructed as to lie on a relatively smooth surface and having a raised platform portion with a cup simulating opening adjacent one end thereof whereby to provide a substantial ball rolling surface as an approach to the cup simulating opening, and a plurality of spaced and angularly positioned hazards on said ball rolling surface some of which hazards are arranged about the opening so as to form a path for the ball when the ball is played up on the platform from one end of the unit and to form a guard for said opening when the ball is played up on the platform from the opposite end of the unit.

4. A unit for a miniature golf game so constructed as to lie on a relatively smooth surface and having a platform portion with two diagonally spaced openings therein, each opening simulating a golf cup, and various hazards on said device to influence the progress of a ball toward the cup simulating openings, whereby to provide on the platform portion overlapping ball rolling approaches for the cup simulating openings.

5. A unit for a miniature golf game so constructed as to lie on a relatively smooth surface, having a raised platform portion with two diagonally spaced openings therein, inclined surfaces leading up to opposite ends of the platform, hazards on said surfaces and platform, some of which hazards are arranged about each opening so as to form a path for the ball when the ball is played up on the platform portion from one end of the unit and to form a guard for each opening when the ball is played up on the platform from the opposite end of the unit.
